UNITED STATES PATENT OFFICE.

JOHN W. MEAKER, OF DETROIT, MICHIGAN.

SPARK-PLUG CONSTRUCTION.

1,149,388.

Specification of Letters Patent. Patented Aug. 10, 1915.

Application filed July 19, 1913. Serial No. 780,019.

To all whom it may concern:

Be it known that I, JOHN W. MEAKER, a citizen of the United States of America, residing at Detroit, in the county of Wayne 5 and State of Michigan, have invented certain new and useful Improvements in Spark-Plug Construction, of which the following is a specification, reference being had therein to the accompanying drawings.

10 This invention relates to spark plugs and to an arrangement thereof that not only simplifies the construction but also assists in preventing the lodgment of moisture in the sparking terminals.

15 The invention consists in the matters hereinafter set forth and particularly pointed out in the appended claims.

In the drawings, Figure 1 is a view partially in elevation and partially broken away and in section of one form of spark plug that embodies features of the invention; Fig. 2 is a plan view of the lower end thereof; Fig. 3 is a view, partially in elevation and partially broken away and in section of a slight modification of the device; Fig. 4 is a plan view of the lower end of the modification; and Fig. 5 is a view in detail of the modification.

20 Referring to the drawings, a body 1 of suitable insulating material has a flange 2 intermediate its ends and a central axial aperture that is preferably counterbored at the upper end and is likewise enlarged at the lower end. An exteriorly screw-threaded nipple 3 has a polygonal bore in which the body 1 is supported, preferably on a collar 4, an exterior bushing 5 clamping the parts in position. Preferably the exterior bushing is made of a polygonal stock bar 25 with a lower seating flange 6 turned up on its lower end and bent outwardly so that the flange has the necessary external diameter. At the upper end an inner annular flange 7 bears against a suitable packing 30 washer 8 that is interposed between the flange of the body and the bushing flange 7.

45 A stem 9 that passes through the central aperture of the body and carries at its lower end a suitably disposed terminal 10 that is in co-operative relation to a pair of depending lugs 11 formed by cutting away a portion of the bushing 3. Preferably the terminal is in the form of an inwardly concaved plate with projections 12 thereon that may be brought into the required distance from the lugs 11 by rotation of the stem in the

body. Preferably the stem is held at its upper end by a suitably arranged head 14 with a spring member 15 bearing against a washer 16 and the countersunk end of the head, the spring permitting expansion and contraction of the members. As a matter of good mechanical construction the polygonal bore of the member 3 may be formed as described in my co-pending application Serial Number 777,742 wherein a screwthread is first formed in the wall and then a broach forced through that cuts away a part of the projecting thread.

50 In the modification shown in Figs. 3, 4 and 5 a stem 17 has a depending conical head 18 that has co-operative relation with suitable inturned terminals 19 formed or secured on the bushing 3. As indicated in Fig. 5, the conical head on the stem is in co-operative relation to the vertical thin edges 21 of the inturned and upright terminals 19 on the nipple.

55 This construction provides a light and durable spark plug that is cheaply constructed of stock material and that has a body of sufficient diameter to prevent breakage, a common defect in spark plugs of the usual type owing to the material of which the body is usually made.

60 A further feature is the disposition of the depending outwardly flared points of the stem, terminal or head whereby moisture that may collect on the plug does not concentrate at the point and does not tend to 65 bridge the spark gaps and thereby render the plug useless.

65 Obviously, changes in the details of construction may be made without departing from the spirit of my invention and I do not 70 care to limit myself to any particular form or arrangement of parts.

75 What I claim is:—

1. A spark plug comprising an exteriorly screwthreaded nipple, a body of insulating material therein secured by a central flange on the upper end thereof, a bushing screw-threaded over the nipple and provided with an internal flange at its upper end that 80 clamps the body flange against the nipple and with a lower flange that is outturned to form a shoulder, depending sparking terminals on the nipple having sharply defined 85 sparking edges, a stem in the body and a terminal head on the stem that forms spark gaps with the nipple terminal having upwardly divergent limiting edges.

2. A spark plug comprising an exterior nipple, a body of insulating material inserted in the nipple, an enlarged central portion of the body forming a shoulder supported by
- 5 the nipple, a bushing screwthreaded over the nipple and adapted to hold the enlarged central portion thereof to seat, depending sparking terminals on the nipple having sharply defined edges substantially parallel
- 10 to the body axis, an axial stem in the body,

and a terminal head on the stem that tapers upwardly and forms divergent spark gaps with the edges of the nipple terminals.

In testimony whereof I affix my signature in presence of two witnesses.

JOHN W. MEAKER.
